UNITED STATES PATENT OFFICE.

JOHN P. SHUMWAY, OF LOS ANGELES, CALIFORNIA.

CONCENTRATOR.

No. 838,468.

Specification of Letters Patent.

Patented Dec. 11, 1906.

Application filed April 12, 1904. Serial No. 202,830.

To all whom it may concern:

Be it known that I, JOHN P. SHUMWAY, a citizen of the United States, residing at Los Angeles, in the county of Los Angeles and 5 State of California, have invented new and useful Improvements in Concentrators, of which the following is a specification.

My invention relates to means to extract the valuable metals from sand or other substances in which they are found without the use of water, and is particularly adapted for 10 use in placer-mining.

It consists of a series of tables mounted one a little higher than the other, each table 15 having an inclination downward from the head to the tail end thereof, and means to impart a lateral rocking and agitating oscillating motion thereto.

The object of my invention is to extract 20 precious metal from the substances in which it is found without the use of water. I accomplish this object by means of the apparatus described herein and shown in the accompanying drawings, in which—

25 Figure 1 is a perspective view of a concentrator embodying my invention. Fig. 2 is a central longitudinal section of one of the concentrator-tables. Fig. 3 is an enlarged transverse section taken on line 3 3 of Fig. 1. 30 Fig. 4 is a transverse section of the hopper or receptacle from which the material to be operated on is fed to the concentrator-table.

In the drawings, A is the frame upon which the concentrator-tables B are operatively 35 mounted. The earth or material containing the precious metal to be operated on is first fed to the receiving-hopper C, and is fed therefrom through the aperture C' in the bottom thereof. This aperture is immediately 40 above the head of the concentrating-table. Rotatively mounted in the bottom of the hopper and immediately above and to one side of the discharge-aperture C', I mount the rotating shaft or drum D, operated by the 45 belt E in the direction indicated by the arrow in Fig. 1. In the bottom of the hopper I place the false bottom F, with an inclination downward from the side of the hopper to a point immediately over the rotating 50 drum D, by means of which the contents of the hopper will be fed down to and upon the head of the first concentrator-table. To regulate the amount of earth fed to the concentrator-tables, I have provided the regulator G, having an inclination downward 55 from the front side of the hopper to the top

of the drum. The opening between the regulator G and the drum is regulated by the thumb-nut H. By this construction all the substances which are placed in the hopper 60 will be fed down and through the discharge-openings C' to the concentrator-tables.

My concentrator-table has a canvas or other porous material I extending from side to side and from the head to the foot of the 65 table and securely attached thereto. On top of the canvas or other porous material is provided a series of strips J, placed lengthwise of the table and edgewise thereon, the bottom edges thereof resting upon the canvas.

Below the canvas I place a like number of longitudinal strips J', arranged to register with the strips J above, they securely holding the canvas between them. The bottom 75 longitudinal strips J' are fastened to the cross-supporting strips K, which rest loosely upon strips or cleats (not shown) fastened to the inside surface of the sides of the table or air-box. Beneath these cross-supporting 80 strips I provide a number of agitators or rockers L, pivoted on an arm l, projecting downwardly from the center thereof, as shown in Fig. 3, the purpose of which is to impart an agitating motion to these strips J'. 85 These agitators are caused to rock upon their bearings L' by the lateral movement of the concentrator-tables, as will be herein-after explained. The lateral motion of the concentrator-tables will throw one of the projecting ends of the agitator upward and against the cross-supporting strips K, and the reverse movement will cause the other end of the agitator to contact with the cross-supporting strip, and thereby agitate the same, 95 which of course will agitate the canvas resting thereon. This will cause material on the canvas to be agitated, as herein explained. When the concentrator-table is moved laterally, these agitators will rock on their pivoted 100 supports and contact with and agitate the canvas.

Motion is imparted to the apparatus through the driving-pulley M in the direction indicated by the arrow thereon. On the 105 main driving-shaft M' is mounted a pulley N, having on the periphery thereof an irregular groove N', into which projects the lug O' on the table operating-shaft O. As the pulley is rotated it will impart a longitudinal movement to the shaft O and a lateral movement 110 to the table B and to the shaking frame T,

which is firmly secured to the shaft O by means of set-screws t, each end of which frame rests on rocking supports U, mounted on the frame of the concentrator.

5 The concentrator-table below the canvas top therein is air-tight, forming an air-chamber B'', and air is fed thereinto through the air-pipes P, which will pass up and into the air-chamber below the canvas, as shown in 10 Fig. 1. These pipes are preferably made of canvas or other pliable material. The air is forced into and distributed through the in- 15 closed table or air-box by means of flues from a blower or other means, (not shown,) the com- 20 pression of the air being automatically regu- 25 lated by valves placed in the main air-pipes coming from the blower. The air passes through the canvas and partially suspends the light and undesired portion of the sub- 30 stance operated on, which, with the longitudi- 35 nal inclination together with the agitation of the table, will pass along down and upon the second table of the machine, and finally be discharged upon the waste dump, the values being held upon the canvas.

When the hopper is emptied or when the desired quantity of material has been worked over the concentrator, the concentrator-tables are dumped or turned into a vertical 30 position. The tables being pivotally mounted in their center on the shaft O for that purpose the concentrates will fall upon a conveyer-belt S, Fig. 1, driven by a roller V, operatively connected with the driving-shaft M', and 35 will be discharged into a conveyer or other receptacle W.

To relieve the lug O' of the strain which would be placed thereon by the lateral movement of the concentrator-tables, I have pro- 40 vided the springs Y to receive the impact caused by this lateral movement. On each 45 end of the shaft O is mounted the rectangular shaking-frame T, through the center of which is passed the shaft O. This rectangular frame is mounted on the swinging supports U, which are pivoted on the main frame. This frame carries at one end thereof a detent-bolt T', adapted to be seated in a hole in the 50 table B and hold the frame in alignment with the table while the bolt is in place therein. Now when it is desired to tip the table the bolt is withdrawn by hand, when the table can be tilted into any position desired. This 55 rectangular frame is preferably made of metal and forms a bearing upon which to support the concentrator-table. On the outer side of the main frame and secured thereto is placed an iron bracket X, through which the ends of the shaft O pass. Between the bracket and 60 the rectangular frame and encircling the

shaft O, I have placed a spring Y, the purpose of which is to act as a cushion to prevent the table from stopping too abruptly at the end of its lateral movements.

It is essential to the successful working of 65 my invention that sufficient pressure be placed on the air beneath the canvas to move the worthless particles thereon and not to disturb the valuable particles. This is accomplished by regulating the pressure applied to the air-chamber in any conventional manner adapted for that purpose.

Having described my invention, what I claim as new, and desire to secure by Letters Patent, is—

1. The herein-described apparatus for separating ore without the use of water, comprising a plurality of concentrator-tables pivotally mounted in a supporting-frame and arranged to normally have an inclination 80 downward from the head to the foot thereof, one table being mounted higher than the other and arranged to discharge the waste from the first or highest table onto the table next below the same; an air-tight casing beneath the canvas top of the table, a canvas or other porous covering thereon; and means to vibrate said covering; means to supply air to the air-chamber below the covering; and means substantially as shown to impart a vibratory motion to said table in combination with a carrying-belt disposed below the concentrator-table and adapted to receive the contents of the table when the tables are thrown into the vertical position, the said 85 carrying-belt extending under all the concentrator-tables and being operatively connected with the main driving-shaft and arranged to carry the material dumped thereon into a receptacle and means to feed the tables with 90 the substance to be operated on.

2. The combination with a concentrator-table, loosely mounted near its longitudinal center on a shaft and provided with a hole in its side, of frames at both sides of the table 105 keyed to the shaft each frame carried by swinging supports, one of said frames carrying a bolt at a point remote from the shaft, adapted to be seated in the said hole in the table, and a spring on the shaft between an 110 abutment on the concentrator-frame, and the frame carrying the bolt.

In witness that I claim the foregoing I have hereunto subscribed my name this 16th day of March, 1904.

JOHN P. SHUMWAY.
